UNITED STATES PATENT OFFICE.

CHARLES B. MILLER, OF CHICAGO, ILLINOIS, AND ORVILLE D. COTTON, OF DETROIT, MICHIGAN; SAID MILLER ASSIGNOR TO SAID COTTON.

FURNACE.

SPECIFICATION forming part of Letters Patent No. 721,818, dated March 3, 1903.

Application filed June 5, 1902. Serial No. 110,280. (No model.)

To all whom it may concern:

Be it known that we, CHARLES B. MILLER, residing at Chicago, in the county of Cook and State of Illinois, and ORVILLE D. COTTON, residing at Detroit, in the county of Wayne and State of Michigan, citizens of the United States, have invented certain new and useful Improvements in Furnaces, of which the following is a full, clear, and exact specification.

10 Our invention relates more particularly to that class of furnaces in which a rotary or oscillatory clinker-bar is employed for working the clinkers from the grate, the same being usually located at the lower ends of converging grates between two frame members toward which the clinkers and other refuse slide; and our invention has for one of its important objects to provide means for preventing the clinkers from gorging the passages between these frame members and the clinker-bar.

15 Another object of our invention is to so arrange one or more perforated steam-pipes for supplying steam to the clinkers as to shield 20 and protect the same from injury.

With these ends in view our invention consists in certain features of novelty in the construction, combination, and arrangement of parts by which the said objects and certain 25 other objects hereinafter appearing are attained, all as fully described with reference to the accompanying drawings and more particularly pointed out in the claims.

In the said drawings, Figure 1 is a plan 30 view of the clinker-bar and the frame members with connected parts between which the bar is situated, the grate-bars being omitted. Fig. 2 is a vertical section on the line 2 2, Fig. 3; and Fig. 3 is a transverse section on the 35 line 3 3, Fig. 1, also showing the grates in dotted lines and additional steam-pipes thereunder.

1 is the clinker-bar, having teeth or wings 2, and 3 4 are the frame members of the grate, between which the clinker-bar is usually situated and downwardly toward which the grates slope or converge, as shown by the dotted lines 5 6 in Fig. 3, the clinker-bar 1 being journaled in any suitable bearings (not necessary to illustrate) and, if desired, supported

at intervals by cross-bars 7. In furnaces of this character it is understood that the clinkers and other refuse, but particularly the clinkers, slide down the grates 5 6 to the space between the frame members 3 4 and are forced 55 through the frame members into the ash-pit below by the continued or occasional rotation of the clinker-bar; but owing to the converging character of the grates the clinkers frequently gorge the passage between the clinker-bar and that one of the frame members 3 4 toward which the bar rotates, this being also due in many instances to the clinkers being larger than the space between the bar and the frame member through which they have 60 to pass. In order to avoid this objectionable result, we provide a crusher-bar, preferably, on the face of each of the frame members 3 4. These crusher-bars are shown at 8 9 as sectional bars recessed in the faces of the frame 65 members 3 4 and secured in place by a suitable number of bolts 10, passing through the frame members, and in order that the upward motion of the wings or teeth of the clinker-bar may not tend to dislodge the crusher-bars the latter 70 are provided with dovetailed or V-shaped projections 11, rested in complementary recesses in the frame members 3 4, so as to be held at the lower edges, while the bolts hold them at the upper edges. The crusher-bars are preferably toothed, as shown at 12, and these teeth 12 project into close proximity to the sweep of the teeth 2 on the clinker-bar, so as to coöperate with the latter teeth in crushing the clinkers, which first lodge upon the 75 crusher-bars and their teeth and are thereafter disintegrated by the action of the teeth 2. These crusher-bars 8 9 also form protecting-edges for shielding one or more steam-pipes 80 13, which are provided with perforations 14, 90 that supply steam to the clinkers above the clinker-bar, and thereby render the clinkers brittle and capable of being crushed by the clinker-bar, as will be understood. These steam-pipes 13 are arranged contiguous to 95 the frame members 3 4 and close up under the teeth 12, so that the steam from the perforations 14 may pass upwardly between the teeth, while the latter at the same time shield the pipes from injury. In Fig. 3 we have 100

shown additional perforated steam-pipes 16, arranged under the grates 5 6 for a similar purpose.

Having thus described our invention, what we claim as new therein, and desire to secure by Letters Patent, is—

1. In a furnace the combination of a rotary clinker-bar, frame members between which said clinker-bar is journaled, perforated steam-pipes arranged lengthwise and at both sides of said clinker-bar and removable ledges situated on said frame members above and protecting said steam-pipes, said ledges being arranged to coact with said clinker-bar in crushing the clinkers, substantially as set forth.

2. In a furnace the combination of a rotary clinker-bar, frame members between which said bar is journaled having dovetailed recesses in their opposed faces, crusher-bars having dovetailed portions fitting in said re-

cesses, bolts removably securing said crusher-bars to said frame members adjacent to the sides of said clinker-bar and one or more perforated steam-pipes arranged under and protected by said crusher-bars, substantially as set forth. 25

3. In a furnace the combination of a rotary clinker-bar, frame members between which said bar is journaled, crusher-bars projecting laterally from the opposed faces of said frame members and having their edges situated adjacent to the sides of said clinker-bar and perforated steam-pipes arranged under and shielded by said crusher-bars with their 30 perforations directed toward said clinker-bar, substantially as set forth. 35
